FOUNTAIN PEN BARREL

Andréa N. Kahla, Cairo, Egypt

Application August 5, 1952, Serial No. 20,909

Term of patent 3½ years

(Cl. D74—17)

To all whom it may concern:

Be it known that I, Andréa N. Kahla, a citizen of Egypt, residing at Cairo, Egypt, have invented a new, original, and ornamental Design for a Fountain Pen Barrel, of which the following is a specification, reference being had to the accompanying drawing, forming part thereof.

Figure 1 is a front elevational view of a fountain pen barrel showing my new design;

Figure 2 is an end elevational view thereof looking from the pen point end; and

Figure 3 is a fragmentary side elevational view of the pen point end.

My design for a fountain pen barrel is characterized by the band extending around the barrel near the nib, said band being comprised of

uniformly spaced ridges disposed longitudinally of the barrel.

I claim:

The ornamental design for a fountain pen barrel, as shown and described.
